(57) **ABSTRACT**

A rehabilitative and corrective system, a strength building system, a recovery system, a muscle activation system, and methods of use are presented. The invention provides a stable platform with multiple equipment attachments, an adjustable set of pillars with a stable crossbar, and a storage compartment. The invention is collapsible for movement and storage. The invention is also adjustable to fit the needs of various individuals and exercises. The systems and methods of use provide for a variety of rehabilitative and human performance movements which provide for a health professionals intent and musculoskeletal needs. The stable platform provides for vertical and horizontal adjustment. A center bar of the invention includes pillar cams and can be adjusted to rotate or remain stable. The invention provides for space savings and can be used to increase joint mobility, muscle activation, release, and strength, and other individual needs and goals.

**REHABILITATIVE AND CORRECTIVE
SYSTEM, STRENGTH SYSTEM, RECOVERY
SYSTEM, MUSCLE ACTIVATION SYSTEM,
AND METHODS OF USE**

**CROSS-REFERENCE TO RELATED
APPLICATIONS**

The present application claims priority to the U.S. Provisional Patent Application No. 63/276,735 which was filed on Nov. 8, 2021, which is hereby incorporated by reference herein in its entirety, including any figures, tables, or drawings.

FIELD OF THE DISCLOSURE

This disclosure relates to a rehabilitative and corrective system, a strength building system, a recovery system, a muscle activation system, and methods of use. More specifically, and without limitation, the present disclosure relates to an adjustable rehabilitative and corrective platform and corresponding apparatuses that provide equipment to help a user build strength, recover, activate muscles, and release.

COPYRIGHT NOTICE

At least a portion of the disclosure of this patent document contains material that is subject to copyright protection. The copyright owner has no objection to the facsimile reproduction by anyone of the patent document or the patent disclosure, as it appears in the Patent and Trademark Office patent files and/or records, but otherwise reserves all copyright rights whatsoever. The following notice applies to the software and data as described below and in the drawings that form a part of this document. Copyright Jason Mitchler and Tyler Christiansen. All rights reserved.

BACKGROUND OF THE DISCLOSURE

Physical rehabilitation is a practice which is well known in the art. Physical rehabilitation, also associated with medicine and sports medicine, often involves care, treatment, and/or exercises and/or motions which help a person and/or patient improve physical abilities and/or recover lost physical abilities that may improve daily life. Some of the physical abilities may be lost because of injury, trauma, disease, aging, or otherwise. Physical rehabilitation is a process, often a medical prognosis, of helping a patient and/or individual improve function and quality of life.

Physical rehabilitation may involve doctors, chiropractors, physical therapists, and various types of equipment. A number of rehabilitative and human performance professionals and various types of equipment exist in the state of the art. A large variety of equipment exists for increasing mobility, alignment, strength, and improving recovery and/or improving recovery times for individuals.

When utilized correctly, various equipment in the state of the art can be effective in assisting improvement of mobility and strength for an individual. Similarly, this equipment, along with proper guidance, can also be effective in assisting with muscle activation and release. In this way, there exists equipment which can assist with rehabilitation and performance of individuals.

However, the current state of the art requires many pieces of equipment. Oftentimes, rehabilitation involves a huge facility to accommodate the various types of equipment and

2

space required for such equipment. This is how the industry has operated for a long time; the rehabilitative industry. Oftentimes various pieces of equipment are required for a single type of move or guided rehabilitation.

5 Complicating matters further, the bulk of some types of equipment often doesn't fit appropriately in a required space and/or fits awkwardly into a required space. Furthermore, some equipment and/or exercises are performed on an unstable surface and/or in a circumstance of high risk and/or in a circumstance where safety may be an issue. These types of problems have plagued clinics and performance facilities. This has become known as common practice and fitting as much equipment as possible into a space is industry standard.

10 15 Thus, there is a need in the art for a single, well-defined spatial system which provides rehabilitation. Furthermore, while the industry practice is to utilize more equipment, there is a need in the art for a system which provides mobility enhancement, alignment, strength, recovery tools and functions in a compact and easily accessible system. These and other needs, such as accessibility and safety are needed. This need would allow for smaller offices and/or spaces. Said another way, this system would allow for use in more spaces, such as homes, or the like. In this way, the 20 25 various functionality of the disclosure herein, provides for a plurality of different functions and services as an all-in-one system, utilizing a minimal amount of space, while providing rehabilitative and performance professionals a more than adequate, functional workspace to utilize skills and provide rehabilitation and more in a safe environment.

Furthermore, the present disclosure provides for meeting musculoskeletal needs of various individuals of various shapes and sizes, while also providing a plurality of storage locations for accessories and equipment. Furthermore, the 30 35 present system can be stored easily, saving space and/or providing additional space when not in use. Similarly, the present disclosure also provides portability so that the system may be easily moved from one location to another.

The disclosure herein provides these advantages and 40 others, solves long-felt needs in the art, goes against the art practice of additional and numerous amounts of equipment, and provides other functionality, features, and advantages, as will become clear from the specification and claims provided.

SUMMARY OF THE DISCLOSURE

The present disclosure—the rehabilitative and corrective system, a strength building system, a recovery system, a muscle activation system, and methods of use—provides the state of the art with an adjustable rehabilitative and corrective platform and corresponding apparatuses that provide equipment to help a user build strength, recover, activate muscles, and release. The rehabilitative and corrective system provides for an all-in-one system which archives the functionality of many different pieces of equipment that would otherwise be required for rehabilitation practices, among other practices.

Said another way, the present disclosure provides the state 60 of the art with various advantages over the existing state of the art. The rehabilitation and corrective system fills various needs, long-felt in the art, by providing a stable system, safe to use, with multiple attachments, an adjustable set of pillars with a stable rotating crossbar, storage compartments, and various other rehabilitative equipment for use in rehabilitation 65 which can be customized to the needs and/or requirements of an individual.

The present disclosure provides the state of the art with an activation and release platform. Furthermore, the present disclosure advantageously fills deficiencies in the state of the art by providing a stable platform with multiple equipment attachments and storage—in a way which eliminates the need for numerous pieces of equipment in a work space. Furthermore, the present disclosure provides the state of the art with a stable rotating crossbar and other moveable pieces for operation and/or use. Furthermore, the present disclosure provides the state of the art with a storage compartment for various components such as dowels and other rehabilitative equipment and the like; to be utilized based on an individual's needs.

Thus, it is a primary object of the disclosure to provide a rehabilitative and corrective system, a strength building system, a recovery system, a muscle activation system, and methods of use that improves upon the state of the art.

Another object of the disclosure is to provide a rehabilitative and corrective system, a strength building system, a recovery system, a muscle activation system, and methods of use that includes a frame.

Yet another object of the disclosure is to provide a rehabilitative and corrective system, a strength building system, a recovery system, a muscle activation system, and methods of use that includes a platform.

Another object of the disclosure is to provide a rehabilitative and corrective system, a strength building system, a recovery system, a muscle activation system, and methods of use that includes a stable platform that improves the safety of a user.

Yet another object of the disclosure is to provide a rehabilitative and corrective system, a strength building system, a recovery system, a muscle activation system, and methods of use that can be folded for storage and/or portability.

Another object of the disclosure is to provide a rehabilitative and corrective system, a strength building system, a recovery system, a muscle activation system, and methods of use that includes storage compartments for components.

Yet another object of the disclosure is to provide a rehabilitative and corrective system, a strength building system, a recovery system, a muscle activation system, and methods of use that can be opened and closed.

Another object of the disclosure is to provide a rehabilitative and corrective system, a strength building system, a recovery system, a muscle activation system, and methods of use that provide various attachments for additional functionality.

Yet another object of the disclosure is to provide a rehabilitative and corrective system, a strength building system, a recovery system, a muscle activation system, and methods of use that provides for the ability to adjust various components for various sizes of a user and/or number of users.

Another object of the disclosure is to provide a rehabilitative and corrective system, a strength building system, a recovery system, a muscle activation system, and methods of use that can be locked into various positions for safety.

Yet another object of the disclosure is to provide a rehabilitative and corrective system, a strength building system, a recovery system, a muscle activation system, and methods of use that provides for platform material to be interchangeable.

Another object of the disclosure is to provide a rehabilitative and corrective system, a strength building system, a

recovery system, a muscle activation system, and methods of use that can be configured to various users for various exercises and/or activations.

Yet another object of the disclosure is to provide a rehabilitative and corrective system, a strength building system, a recovery system, a muscle activation system, and methods of use that are collapsible.

Another object of the disclosure is to provide a rehabilitative and corrective system, a strength building system, a recovery system, a muscle activation system, and methods of use that saves space for a user.

Yet another object of the disclosure is to provide a rehabilitative and corrective system, a strength building system, a recovery system, a muscle activation system, and methods of use that provides for configuration adjustments to modify exercises.

Another object of the disclosure is to provide a rehabilitative and corrective system, a strength building system, a recovery system, a muscle activation system, and methods of use that can be easily stored.

Yet another object of the disclosure is to provide a rehabilitative and corrective system, a strength building system, a recovery system, a muscle activation system, and methods of use that provides for storage of accessory equipment.

Another object of the disclosure is to provide a rehabilitative and corrective system, a strength building system, a recovery system, a muscle activation system, and methods of use that provides a storage compartment for accessory equipment.

Yet another object of the disclosure is to provide a rehabilitative and corrective system, a strength building system, a recovery system, a muscle activation system, and methods of use that provides a storage compartment for platform equipment.

Another object of the disclosure is to provide a rehabilitative and corrective system, a strength building system, a recovery system, a muscle activation system, and methods of use that provides a stable platform during exercise.

Yet another object of the disclosure is to provide a rehabilitative and corrective system, a strength building system, a recovery system, a muscle activation system, and methods of use that provides for the ability to attach multiple pieces of equipment to a single piece of equipment.

Another object of the disclosure is to provide a rehabilitative and corrective system, a strength building system, a recovery system, a muscle activation system, and methods of use that provide adjustable pillars and adjustable cross-bars.

Yet another object of the disclosure is to provide a rehabilitative and corrective system, a strength building system, a recovery system, a muscle activation system, and methods of use that saves facility and/or clinic space.

Another object of the disclosure is to provide a rehabilitative and corrective system, a strength building system, a recovery system, a muscle activation system, and methods of use that benefits a patient based on individual musculoskeletal needs.

Yet another object of the disclosure is to provide a rehabilitative and corrective system, a strength building system, a recovery system, a muscle activation system, and methods of use that provides new solutions for a user in exercise position and musculoskeletal needs.

Another object of the disclosure is to provide a rehabilitative and corrective system, a strength building system, a recovery system, a muscle activation system, and methods of use that are easy to use.

Yet another object of the disclosure is to provide a rehabilitative and corrective system, a strength building system, a recovery system, a muscle activation system, and methods of use that are safe to use.

Another object of the disclosure is to provide a rehabilitative and corrective system, a strength building system, a recovery system, a muscle activation system, and methods of use that are stable and accurate.

Yet another object of the disclosure is to provide a rehabilitative and corrective system, a strength building system, a recovery system, a muscle activation system, and methods of use that provide a variety of restrictions in movement.

Another object of the disclosure is to provide a rehabilitative and corrective system, a strength building system, a recovery system, a muscle activation system, and methods of use that are relatively affordable.

Yet another object of the disclosure is to provide a rehabilitative and corrective system, a strength building system, a recovery system, a muscle activation system, and methods of use that are robust.

Another object of the disclosure is to provide a rehabilitative and corrective system, a strength building system, a recovery system, a muscle activation system, and methods of use that are quick and efficient to adjust.

Yet another object of the disclosure is to provide a rehabilitative and corrective system, a strength building system, a recovery system, a muscle activation system, and methods of use that are high quality.

These and other objects, features, or advantages of the present disclosure will become apparent from the specification and claims.

BRIEF DESCRIPTION OF THE DRAWINGS

FIG. 1 is a top, perspective view; the view showing the rehabilitative system; the view showing a platform frame; the view showing a stable top platform; the view showing a first center pillar; the view showing a second center pillar; the view showing a first crossbar; the view showing a second crossbar.

FIG. 2 is a top view; the view showing the rehabilitative system; the view showing a platform frame; the view showing a stable top platform; the view showing a first center pillar; the view showing a second center pillar; the view showing a second crossbar.

FIG. 3 is a side view; the view showing the rehabilitative system; the view showing a platform frame; the view showing a stable top platform; the view showing a first center pillar; the view showing a plurality of angle support features.

FIG. 4 is a front view; the view showing the rehabilitative system; the view showing a platform frame; the view showing a stable top platform; the view showing a first center pillar; the view showing a second center pillar; the view showing a first crossbar; the view showing a second crossbar.

FIG. 5 is a front view of the rehabilitative platform; the view showing the system in the stored position.

FIG. 6 is a side view of the rehabilitative platform; the view showing the system in the stored position.

FIG. 7 is a top view of the rehabilitative platform; the view showing the system in the stored position.

FIG. 8 is a top, perspective view of the rehabilitative platform; the view showing the system in the stored position.

FIG. 9 is a top perspective, exploded view of the rehabilitative platform; the view showing the system in the stored position.

FIG. 10 is a top, perspective view showing the threshold; the view showing the first center pillar; the view showing the second center pillar.

FIG. 11 is a front view showing the threshold; the view showing the first center pillar; the view showing the second center pillar.

10 FIG. 12 is a side view showing the threshold; the view showing the first center pillar.

FIG. 13 is a top, perspective view showing the threshold; the view showing a plurality of angle support features; the view showing the first center pillar; the view showing the second center pillar.

15 FIG. 14 is a front view showing the threshold; the view showing a plurality of angle support features; the view showing the first center pillar; the view showing the second center pillar.

20 FIG. 15 is a side view showing the threshold; the view showing a plurality of angle support features; the view showing the first center pillar.

FIG. 16 is a top, perspective, exploded view showing the threshold; the view showing a plurality of angle support features; the view showing the first center pillar; the view showing the second center pillar.

25 FIG. 17 is a top, perspective view showing the platform frame.

FIG. 18 is a front view showing the platform frame.

30 FIG. 19 is a side view showing the platform frame.

FIG. 20 is a bottom view showing the platform frame.

FIG. 21 is a side view showing the platform frame.

FIG. 22 is a rear view showing the platform frame.

35 FIG. 23 is a top, perspective view showing the platform frame.

FIG. 24 is a front view showing the platform frame.

FIG. 25 is a side view showing the platform frame.

FIG. 26 is a bottom view showing the platform frame.

40 FIG. 27 is a side view showing the platform frame.

FIG. 28 is a rear view showing the platform frame.

FIG. 29 is a top, perspective, exploded view showing the platform frame.

45 FIG. 30 is a top, perspective, exploded view showing the platform frame.

FIG. 31 is a top, perspective view showing the stable top platform; the view showing attachment features; the view showing hinge features.

50 FIG. 32 is a top view showing the stable top platform; the view showing attachment features; the view showing hinge features.

FIG. 33 is a side view showing the stable top platform; the view showing attachment features; the view showing hinge features.

55 FIG. 34 is a top, perspective view showing the stable top platform; the view showing attachment features; the view showing hinge features.

FIG. 35 is a side view showing the stable top platform; the view showing attachment features; the view showing hinge features.

60 FIG. 36 is a top, perspective view showing the platform frame; the view showing the stable top platform; the view showing attachment features; the view showing hinge features; the view showing a bottom support feature; the view showing feet; the view showing attachment features.

65 FIG. 37 is a top, perspective view showing a crossbar.

FIG. 38 is a top, perspective view showing a crossbar.

DETAILED DESCRIPTION OF THE DISCLOSURE

In the following detailed description, reference is made to the accompanying drawings which form a part hereof, and in which is shown by way of illustration specific embodiments in which the disclosure may be practiced. These embodiments are described in sufficient detail to enable those skilled in the art to practice the disclosure, and it is to be understood that other embodiments may be utilized and that mechanical, procedural, and other changes may be made

without departing from the spirit and scope of the disclosure(s). The following detailed description is, therefore, not to be taken in a limiting sense, and the scope of the disclosure(s) is defined only by the appended claims, along with the full scope of equivalents to which such claims are entitled.

As used herein, the terminology such as vertical, horizontal, top, bottom, front, back, end, sides and the like are referenced according to the views, pieces and figures presented. It should be understood, however, that the terms are used only for purposes of description, and are not intended to be used as limitations. Accordingly, orientation of an object or a combination of objects may change without departing from the scope of the disclosure.

Reference throughout this specification to "one embodiment," "an embodiment," "one example," or "an example" means that a particular feature, structure, or characteristic described in connection with the embodiment or example is included in at least one embodiment of the present disclosure. Thus, the appearance of the phrases "in one embodiment," "in an embodiment," "one example," or "an example" in various places throughout this specification are not necessarily all referring to the same embodiment or example. Furthermore, the particular features, structures, databases, or characteristics may be combined in any suitable combinations and/or sub-combinations in one or more embodiments or examples. In addition, it should be appreciated that the figures provided herewith are for explanation purposes to persons ordinarily skilled in the art and that the drawings are not necessarily drawn to scale.

Embodiments in accordance with the present disclosure may be embodied as an apparatus, method, or computer program product. Accordingly, the present disclosure may take the form of an entirely hardware-comprised embodiment, an entirely software-comprised embodiment (including firmware, resident software, micro-code, etc.), or an embodiment combining software and hardware aspects that may all generally be referred to herein as a "circuit," "module," or "system." Furthermore, embodiments of the present disclosure may take the form of a computer program product embodied in any tangible medium.

In the arrangement shown, as one example, a rehabilitative and corrective system, a strength building system, a recovery system, a muscle activation system, and methods of use are presented. In the arrangement shown, as one example, a stable platform with multiple equipment attachments, an adjustable set of pillars with a stable rotating crossbar, and a storage compartment for dowels and other rehabilitative equipment are provided, which can be customized for individual musculoskeletal needs. In this way, the present disclosure provides the state of the art with a novel activation and release platform, which includes a plurality of components and functionality.

System:

With reference to the figures, a rehabilitative and corrective system, a strength building system, a recovery system, a muscle activation system, and methods of use 10 (hereafter referred to as a "rehabilitative system", "a release platform", an "activation platform", a "corrective system", a "strength building system", a "recovery platform", a "muscle activation system", or simply "system") is presented. Rehabilitative system 10 is formed of any suitable size, shape and design.

In the arrangement shown, the strength building platform 10 provides a novel activation and release platform. The corrective system 10 is configured to provide an integrated adjustable pillar component and center bar components with adjustable cams. The adjustable cams are configured to

11

provide the ability to rotate the center bar about an axis. Similarly the adjustable cams are configured to lock the center bar in place and/or adjust the height of the center bar based on the exercise design.

Furthermore, and in the arrangement shown, the rehabilitative platform **10** is configured as a collapsible platform. In this way, the collapsible platform provides a stable exercise base which can be compacted for storage and space savings. Similarly, the configuration provides for a ninety degree storage position for space and/or exercise modifications, and the like.

Furthermore, and in the arrangement shown, the rehabilitative system **10** includes storage functionality. In other words, system **10** includes a storage compartment (to be further described herein), located conveniently in the platform. This provides for easy access and convenient storage of exercise equipment and other components.

Furthermore, and in the arrangement shown, the center bar provides for an attachment point, in addition to attachment features, for the configuring and/or attachment of accessory exercise equipment. Similarly, this center bar not only provides for attachment of accessory exercise equipment but can also be configured to attach third party and/or other exercise equipment and arrangements not disclosed herein. These alternative configures may vary greatly in treatment and exercise and are hereby contemplated for use.

In the arrangement shown, as one example, system **10** is formed of an integrated pillar and center bar component with integrated adjustable cams. These components provide the ability to rotate and/or lock the center bar. Furthermore, these components are configured to adjust the height of the center bar. These adjustments and/or formations of configuration vary based on the particular exercise and/or movement and/or release and/or activation which is needed and/or desired.

In the arrangement shown, as one example, system **10** includes a collapsible platform that provides a stable exercise location. Furthermore, the stable platform can be compacted and/or stored for space savings. Furthermore, the position of the stable platform can be modified to various orientations for various workout and/or exercise modification requirements.

In the arrangement shown, as one example, activation platform system **10** includes, in the embodiment(s) depicted, a user **12**, a platform frame **20**, a stable platform **40**, a first center pillar **60**, a second center pillar **80**, a first crossbar **100**, and a second crossbar **120**, among other components, features, and functions.

User (or Plurality Thereof):

In the arrangement shown, as one example, system **10** may include a user. User may be any user interacting with or utilizing the system **10**. This may include viewing, controlling, analyzing, manipulating, and/or interacting with system **10**. User is not limited to a single user but may be a plurality of users. Furthermore, user is not limited to a user engaging with and/or exercising with platform **10**. User may also include an instructor such as a medical professional. This medical professional may be a physical therapist, a medical doctor, an assistant, and the like.

Platform Frame:

In the arrangement shown, as one example, system **10** includes a platform frame **20**. Platform frame **20** (also referred to simply as "frame", or "main body") is formed of any suitable size, shape, and design and is configured to provide the overall frame and main structural elements of

12

the system **10**. Additionally, platform frame **20** is configured to provide various attachment features and stabilization features for system **10**.

In the arrangement shown, as one example, platform frame **20** is formed of metal. In the arrangement shown, frame **20** is formed of multiple steel parts which are channel metal and provide a stable structure for handling large weighted movements and the like. In the arrangement shown, as one example, the platform frame **20** is configured to work in concert with other components of system **10**.

In the arrangement shown, as one example, the platform frame **20** is configured to adjust to various positions based on being used and/or stored and/or stowed. Similarly, the platform frame **20** is configured to work and/or integrate with a variety of other components and is also configured as part of the storage system. Furthermore, the platform frame **20** integrates and supports the pillars (to be further described herein).

In the arrangement shown, as one example, the frame **20** extends a length from a first end **22** to a second end **24** between opposing sides **26**, which extend in approximate parallel spaced relations to one another. The frame **20** also includes a top **28** and a bottom **30**. The platform frame **20** also includes a hollow interior **32** of the frame **20** and a plurality of access features **34**, which enable access to the hollow interior **32**.

Additionally, and in the arrangement shown, the platform frame **20** includes a plurality of attachment features **36**. In the arrangement shown, some of the attachment features **34** are apertures designed to accept and/or receive pins therein. Pins and/or locking mechanisms enable other items to be attached to the platform, such as exercise equipment. Similarly, attachment features **36** enable different arrangements and assemblies of the frame to be accommodated. Similarly, attachment features **36** are configured for construction and/or assembly of the frame and/or accommodation of different assemblies of the frame itself. This is especially apparent in the figures, with reference to how the pillars (to be further described herein) are secured to the frame **20**.

In the arrangement shown, frame **20** includes various pins and/or locking pins. Pins are formed of any suitable size, shape, and design and are configured to provide functionality of system **10**. Additionally, pins are configured to provide various attachment features and various locations for attaching equipment, and the like. In this way, the pins provide for 360 degrees of attachment for equipment, such as exercise bands, resistance bands, and the like.

Furthermore, and in the arrangement shown as one example, the frame **20** also includes a threshold **38**. Threshold **38** is configured to fill a gap formed between the plurality of platforms and the center pillars. Said another way, the threshold **38** is configured to protect a user from getting hurt or dropping objects into the gap between the platforms and the center pillar. In the arrangement shown, as one example, the threshold **38** is formed of a rectangular rubber piece. However, other forms of threshold are hereby contemplated for use.

Similarly, in the arrangement shown, as one example, the frame **20** is formed of metal. However, other materials for the configuration and/or construction of the frame **20** are hereby contemplated for use. Some examples include, but are not limited to, polymers, enhanced polymers, metal alloys, fibers, carbon fibers, wood, a combination thereof, and the like. Furthermore, frame **20**, as a sturdy material can be used, particularly when in certain positions for bouncing and/or holding heavy equipment. As one example, a medi-

cine ball may be bounced and/or slammed against the platform and frame as an exercise.

Similarly, in the arrangement shown, as one example, frame **20** is considered to be one frame **20** but may be multiple frames and/or may be more than one frame **20** secured and/or unsecured to one another and/or lined up next to each other. In this way, multiple frames **20** can be safely utilized to increase the rehabilitation area. In this way, one frame is hereby contemplated for use. Similarly two frames are hereby contemplated, three frames, four frames, five frames, six frames, seven frames, or more.

Stable Top Platform:

In the arrangement shown, as one example, system **10** includes a stable top platform **40**. Stable top platform **40** is formed of any suitable size, shape, and design and is configured to provide a safe and supportive platform for which a user engages during various exercises. The stable top platform **40** is configured and situated on top of the platform frame **20**, in one arrangement shown. In this way, the stable top platform **40** is configured as a supportive frame for resisting forces.

In the arrangement shown, as one example, the stable top platform **40** is formed of a generally slender rectangular-like shape which is thin and mat-like. In this way, the stable top platform **40** functions as a safe and effective workout mat and/or platform. Furthermore, and in the arrangement shown as one example, the stable top platform **40** is configured to provide an enclosure for the hollow interior of the frame **20**, in addition to providing a foldable surface and/or replaceable surface for storage, exchanges of material and the like.

In the arrangement shown, as one example, the stable top platform **40** extends a length from a first end **42** to a second end **44** between opposing sides **46**. The stable top platform **40** also includes a top **48** and a bottom **50**. The stable top platform **40** also includes a plurality of attachment features **52** for securing the stable top platform **40** to the frame **20**. In some arrangements, it is also contemplated that this is a frictional and/or force fit in which the platform is held in place by the frame and/or gravity and/or the user.

Furthermore, and in the arrangement shown, the stable top platform **40** includes folding features **54**. The folding features **54** are formed of any suitable size, shape, and design and are configured to provide a hinge-like functionality near the center of the platform frame which provides that the platform can be folded in a 90-degree configuration; with reference to the figures. Similarly, the stable top platform **40** includes hinge features **56** for the opening of the stable top platforms **40** for easily storing components and the like in the storage area within the hollow interior of the frame **20**.

In the arrangement shown, as one example, the stable top platform **40** is formed of a rubber material. However, other materials for the configuration and/or construction of the frame **20** are hereby contemplated for use. Some examples include, but are not limited to, polymers, enhanced polymers, metal, metal alloys, fibers, carbon fibers, wood, a combination thereof, and the like.

Similarly, in the arrangement shown, as one example, the stable top platform **40** is considered to be one stable top platform **40** but may be multiple top platforms and/or may be more than one top platform **40** secured and/or unsecured to the frames and/or to one another and/or lined up next to each other. In this way, multiple stable top platforms **40** can be safely utilized to increase the rehabilitation area. In this way, one frame is hereby contemplated for use. Similarly, two stable top platforms may be contemplated, three stable

top platforms, four stable top platforms, five stable top platforms, six stable top platforms, seven stable top platforms, or more.

First Center Pillar:

In the arrangement shown, as one example, system **10** includes a first center pillar **60**. First center pillar **60** is formed of any suitable size, shape, and design and is configured to provide support for exercises and a crossbar and/or center bar (to be discussed further herein). In the arrangement shown as one example, the first center pillar **60** extends perpendicular to and/or upward from the frame **20**. The first center pillar **60**, in this way, provides the upward support to be used to attach exercise equipment to and/or attach a plurality of crossbars; crossbars which can subsequently be used in exercises and/or for attachment of equipment.

Furthermore, and in the arrangement shown, the first center pillar is configured to extend upward, telescopically or otherwise, and also twist and/or spin about a vertical axis.

Similarly, in an alternative embodiment, the first center pillar **60** may also be configured to rotate downward such that the top of the pillar can be moved closer to the frame **20** while the bottom of the pillar **60** stays approximately in a centered location. These variations can be useful for various exercises

In the arrangement shown, as one example, the first center pillar **60** includes a first end **62** (nearer the first end of the frame **20**) and a second end **64** (nearer the second end of the frame **20**). The first center pillar **60** also includes opposing sides **66** that form an approximate square or rectangular shape when viewed from the top. Alternative shapes are also contemplated for use. For example, the first center pillar **60** may also be circular in shape when viewed from the top, triangular in shape, or have another shape.

In the arrangement shown, the first center pillar **60** extends a length from the top **68** to the bottom **70** (the bottom being closer to the frame **20** and stable top platform **40**). In the arrangement shown, the first center pillar **60** also includes a telescoping extension which can increase and/or decrease the height of the first center pillar **60**.

In the arrangement shown, as one example, the first center pillar **60** (and plurality of extensions) include a plurality of attachment features **74**. In the arrangement shown, as one example, the plurality of attachment feature **74** are similar to those found on the frame **20**, in that they are designed to accept the attachment of various other components, including crossbars, and other workout and/or exercise equipment and/or medical equipment. In the arrangement shown, as one example, the plurality of attachment features are formed of apertures for accepting pins and the like. Similarly, the telescoping feature may utilize these apertures and/or pins in changing and/or adjusting the height of the extensions.

In this way, system **10** may also include a plurality of locking pins **76**. Locking pins **76** can be utilized for changing the position and/or configurations of system **10**, as well as attaching features and/or extending the heights of the plurality of extensions and/or telescoping features of system **10**.

In the arrangement shown, as one example, the first center pillar **60** also includes a plurality of angle support features **98** (or simply “angle supports”). Angle supports **98** are located nearer the bottom **70** of the first center pillar **60**. The angle supports **98** are formed and configured to secure the first center pillar **60** to the frame **20** and vice versa. In the arrangement shown, the angle supports **98** also include a plurality of attachment features and locking pins which allow the first center pillar **60** to be angled and/or modified

15

to different angles of correspondence to the platform. In the arrangement shown, as one example, two angle support features **98** are utilized which face in approximately opposite direction, and in parallel to the opposing sides of the frame. In the arrangement shown, as one example, the angle support features **98** are near the opposing sides of the frame **20**. Other arrangements and number of angle support features **98** are hereby contemplated for use.

In the arrangement shown, as one example, the first center pillar **60** is formed of metal and/or formed of the same and/or similar material as the frame **20**. However, other materials for the configuration and/or construction of the first center pillar **60** are hereby contemplated for use. Some examples include, but are not limited to, polymers, enhanced polymers, metal, metal alloys, fibers, carbon fibers, wood, a combination thereof, and the like.

Similarly, in the arrangement shown, as one example, the first center pillar **60** is considered to be one first center pillar **60** but may be multiple pillars may be more than one first center pillar **60** secured and/or unsecured to the frames and/or to one another and/or lined up next to each other. In this way, multiple first center pillar **60** can be safely utilized to increase the rehabilitation area and/or provide additional configurations. In this way, one first center pillar is hereby contemplated for use. Similarly, two first center pillars are hereby contemplated for use, three first center pillars are hereby contemplated for use, or more.

Second Center Pillar:

In the arrangement shown, as one example, system **10** includes a second center pillar **80**. Second center pillar **80** is formed of any suitable size, shape, and design and is configured to provide support for exercises and a crossbar and/or center bar (to be discussed further herein). In the arrangement shown as one example, the second center pillar **80** extends perpendicular to and/or upward from the frame **20**. The second center pillar **80**, in this way, provides the upward support to be used to attach exercise equipment to and/or attach a plurality of crossbars; crossbars which can subsequently be used in exercises and/or for attachment of equipment.

Furthermore, and in the arrangement shown, the second center pillar is configured to extend upward, telescopically or otherwise, and also twist and/or spin about a vertical axis. Similarly, in an alternative embodiment, the second center pillar **80** may also be configured to rotate downward such that the top of the pillar can be moved closer to the frame **20** while the bottom of the pillar **60** stays approximately in a centered location. These variations can be useful for various exercises.

In the arrangement shown, as one example, the second center pillar **80** includes a first end **62** (nearer the first end of the frame **20**) and a second end **64** (nearer the second end of the frame **20**). The second center pillar **80** also includes opposing sides **66** that form an approximate square or rectangular shape when viewed from the top. Alternative shapes are also contemplated for use. For example, the second center pillar **80** may also be circular in shape when viewed from the top, triangular in shape, or have another shape.

In the arrangement shown, the second center pillar **80** extends a length from the top **68** to the bottom **70** (the bottom being closer to the frame **20** and stable top platform **40**). In the arrangement shown, the second center pillar **80** also includes a telescoping extension which can increase and/or decrease the height of the second center pillar **80**.

In the arrangement shown, as one example, the second center pillar **80** (and plurality of extensions) include a

16

plurality of attachment features **74**. In the arrangement shown, as one example, the plurality of attachment feature **74** are similar to those found on the frame **20**, in that they are designed to accept the attachment of various other components, including crossbars, and other workout and/or exercise equipment and/or medical equipment. In the arrangement shown, as one example, the plurality of attachment features are formed of apertures for accepting pins and the like. Similarly, the telescoping feature may utilize these apertures and/or pins in changing and/or adjusting the height of the extensions.

In this way, system **10** may also include a plurality of locking pins **76**. Locking pins **76** can be utilized for changing the position and/or configurations of system **10**, as well as attaching features and/or extending the heights of the plurality of extensions and/or telescoping features of system **10**.

In the arrangement shown, as one example, the second center pillar **80** also includes a plurality of angle support features **98** (or simply “angle supports”). Angle supports **98** are located nearer the bottom **70** of the second center pillar **80**. The angle supports **98** are formed and configured to secure the second center pillar **80** to the frame **20** and vice versa. In the arrangement shown, the angle supports **98** also include a plurality of attachment features and locking pins which allow the second center pillar **80** to be angled and/or modified to different angles of correspondence to the platform. In the arrangement shown, as one example, two angle support features **98** are utilized which face in approximately opposite direction, and in parallel to the opposing sides of the frame. In the arrangement shown, as one example, the angle support features **98** are near the opposing sides of the frame **20**. Other arrangements and number of angle support features **98** are hereby contemplated for use.

In the arrangement shown, as one example, the second center pillar **80** is formed of metal and/or formed of the same and/or similar material as the frame **20**. However, other materials for the configuration and/or construction of the second center pillar **80** are hereby contemplated for use. Some examples include, but are not limited to, polymers, enhanced polymers, metal, metal alloys, fibers, carbon fibers, wood, a combination thereof, and the like.

Similarly, in the arrangement shown, as one example, the second center pillar **80** is considered to be one second center pillar **80** but may be multiple pillars may be more than one second center pillar **80** secured and/or unsecured to the frames and/or to one another and/or lined up next to each other. In this way, multiple second center pillar **80** can be safely utilized to increase the rehabilitation area and/or provide additional configurations. In this way, one second center pillar is hereby contemplated for use. Similarly, two second center pillars are hereby contemplated for use, three second center pillars are hereby contemplated for use, or more.

First Crossbar:

In the arrangement shown, as one example, system **10** includes a first crossbar **100**. First crossbar **100** is formed of any suitable size, shape, and design and is configured to provide support for exercises and/or equipment. Said another way, the first crossbar **100** is configured to accept equipment around and/or attached thereto and provide support. In the arrangement shown, as one example, the first crossbar **100** is secured and/or configured horizontally—attached to the first center pillar **60** and the second center pillar **80**. In this way, the first crossbar **100** is configured

between the cams of each the first and second center pillar while maintaining the ability to rotate and/or lock into position.

In the arrangement shown, as one example, the first crossbar 100 extends a length from a first end 102 (having a first end attachment feature 103 for attaching to the first center pillar 60) to a second end 104 (having a second end attachment feature 105 for attaching to the second center pillar 80). Furthermore, and in the arrangement shown, as one example, the first crossbar 100 includes an exterior surface 106 and a hollow interior 108. Alternatively, the crossbar may not have a hollow interior 108, depending on the material and construction and need.

In the arrangement shown, as one example, the exterior surface is relatively smooth and forms the first crossbar 100, which is generally circular in shape when viewed from the end. In the arrangement shown, as one example, this circular shape may be locked into position such that the bar can not rotate about the center axis of the circle, or the first crossbar 100 may be able to rotate freely about the center axis of the circle. Said another way, the crossbar can be secured at different levels of stiffness between the cams of each pillar with the ability to rotate, rotate with resistance of varying levels, and/or lock into position.

In the arrangement shown, as one example, the first crossbar 100 is formed of metal and/or formed of the same and/or similar material as the frame 20. However, the first crossbar 100 may also be formed of other materials. Some examples include, but are not limited to, polymers, enhanced polymers, metal, metal alloys, fibers, carbon fibers, wood, a combination thereof, and the like.

Similarly, in the arrangement shown, as one example, the first crossbar 100 is shown and may be utilized without any additional crossbars. However, multiple crossbars may be utilized. Said another way, multiple crossbars can be safely utilized to functionality and/or add to configuration options. In this way, one crossbar may be used. However, two crossbars may be utilized, three crossbars, four crossbars, five crossbars, or more.

Second Crossbar:

In the arrangement shown, as one example, system 10 includes a second crossbar 120. Second crossbar 120 is formed of any suitable size, shape, and design and is configured to provide support for exercises and/or equipment. Said another way, the second crossbar 120 is configured to accept equipment around and/or attached thereto and provide support. In the arrangement shown, as one example, the second crossbar 120 is secured and/or configured horizontally—attached to the first center pillar 60 and the second center pillar 80. In this way, the second crossbar 120 is configured between the cams of each the first and second center pillar while maintaining the ability to rotate and/or lock into position.

In the arrangement shown, as one example, the second crossbar 120 extends a length from a first end 122 (having a first end attachment feature 123 for attaching to the first center pillar 60) to a second end 124 (having a second end attachment feature 125 for attaching to the second center pillar 80). Furthermore, and in the arrangement shown, as one example, the second crossbar 120 includes an exterior surface 126 and a hollow interior 128. Alternatively, the crossbar may not have a hollow interior 128, depending on the material and construction and need.

In the arrangement shown, as one example, the exterior surface is relatively smooth and forms the second crossbar 120, which is generally circular in shape when viewed from the end. In the arrangement shown, as one example, this

circular shape may be locked into position such that the bar can not rotate about the center axis of the circle, or the second crossbar 120 may be able to rotate freely about the center axis of the circle. Said another way, the crossbar can be secured at different levels of stiffness between the cams of each pillar with the ability to rotate, rotate with resistance of varying levels, and/or lock into position.

In the arrangement shown, as one example, the second crossbar 120 is formed of metal and/or formed of the same and/or similar material as the frame 20. However, the first crossbar 100 may also be formed of other materials. Some examples include, but are not limited to, polymers, enhanced polymers, metal, metal alloys, fibers, carbon fibers, wood, a combination thereof, and the like.

Similarly, in the arrangement shown, as one example, the first crossbar 100 and the second crossbar 120 are shown and may be utilized without any additional crossbars. However, multiple crossbars and/or no crossbars may be utilized. Said another way, multiple crossbars and/or no crossbars can be safely utilized to functionality and/or add to configuration options. In this way, zero crossbar may be used. However, three crossbars may be utilized, four crossbars, five crossbars, six crossbars, or more.

Other Components:

In the arrangement shown, as one example, system 10 may also include a telescoping mechanism for each of the pillars. In this way, the pillars can extend to various heights and increase the number of configurations.

In another example, the center bar may also include a plurality of attachments and/or attachment features such that various activation and release exercises can be attached in a variety of ways. Similarly, multiple pieces of equipment may be attached at once such that a user can move easily and quickly from one piece of equipment and engage a second piece of equipment quickly and easily.

In another example, a support system may be included. The support system is designed and configured to slide into the platform further stabilizing the platform base. In other words, the support system may be extensions in every direction, in some directions, or may be extensions which go downward such as feet, and/or extended feet, to increase stability of the system and safety of the equipment.

In another example, various platform materials may be utilized for different purposes. In some instances, a soft material with a low rigidity factor may be utilized. However, this material may need to be changed out quickly with a high rigidity factor material for a different type of exercise.

In the arrangement shown, as one example, these and other arrangements are hereby contemplated. Other materials and/or components also hereby contemplated for use—which are apparent from the disclosure and figures provided—include, but are not limited to, a full and/or partial assembly of the system 10 having an upright frame weldment, a plurality of posts, a plurality of gussets, a plurality of channels, a plurality of caps, a plurality of plungers—pins, a plurality of nuts, a plurality of welds, and a plurality of knobs, among other components, features and functionality.

Furthermore, and in the arrangement shown as one example, other materials and/or components also hereby contemplated for use—which are apparent from the disclosure and figures provided—including, but not limited to, a foldable floor ramp assembly having a wood platform, a stiffener, a folding frame, a bracket, a pivot, a stiffener with apertures, a wood platform folding frame, a wheel chair ramp, a leveling pad, a plurality of nuts, a plurality of latches, a plurality of hinges, a plurality of washers, a

19

plurality of screws, a plurality of fasteners, a plurality of hinges, a plurality of bolts, nuts, and washers, a plurality of strips (made of neoprene or otherwise), and a plurality of rivets, among other components, features, and functionality.

Furthermore, and in the arrangement shown as one example, other materials and/or components also hereby contemplated for use—which are apparent from the disclosure and figures provided—including, but not limited to, a foldable floor assembly without a ramp having a platform, a stiffener, a bracket, a pivot, a stiffener, a hing, a folding frame, a leveling pad, a nut, a latch, a catch, a hing, a bolt, a nut, a washer, a screw, a strip, a rivet, and a washer, or a plurality of any thereof, among other components, features, and functionality.

Furthermore, and in the arrangement shown as one example, other materials and/or components also hereby contemplated for use—which are apparent from the disclosure and figures provided—including, but not limited to, a rotating bar assembly having a plurality of bar mounts with or without pins, a mount, a stock, a tube, a bracket, a plunger, a bolt, a washer, a bearing, a nut, a handle, a tubing, a rotating bar end, a spring, or a plurality of any thereof, among other components, features, and functionality.

Furthermore, and in the arrangement shown as one example, other materials and/or components also hereby contemplated for use—which are apparent from the disclosure and figures provided—including, but not limited to, a barbell support assembly having a support, a weight, a plate, a pin, a pivot, a screw, or a plurality of any thereof, among other components, features, and functionality.

Furthermore, and in the arrangement shown as one example, other materials and/or components also hereby contemplated for use—which are apparent from the disclosure and figures provided—including, but not limited to, a pull-up bar assembly having a bar, a pull-up, a bracket, a mounting system, an adjustable upright, a spacer, a folding platform pivot, or a plurality of any thereof, among other components, features, and functionality.

Furthermore, and in the arrangement shown as one example, other materials and/or components also hereby contemplated for use—which are apparent from the disclosure and figures provided—including, but not limited to, a transport roller assembly having a plurality of sides of a transport roller, an angle, a tube, a wheel, an abdominal wheel (or “ab wheel”), a bearing, a bolt, a nut, a pivot bolt, a pivot nut, a washer, a pull-up bar, a pull-up bar mount, a leveling pad, or a plurality of any thereof, among other components, features, and functionality.

Furthermore, and in the arrangement shown as one example, system 10 may also include an accessible ramp. Accessible ramp is formed of any suitable size, shape, and design and is configured to provide access to system 10. Access is provided by a generally smooth surface to provide a means for accessing system 10 by wheelchair, and the like.

Furthermore, and in the arrangement shown, as one example, an accessible ramp also provides a platform for various exercise purposes. For example, the ramp provides an angled ramp which can be engaged for body weighted squats, squats, heel raises and/or calf raises, among other exercise engagements.

In addition to the above identified features, options, controls, and components, system 10 may also include other features and functionalities, among other options, controls, and components.

20

In Operation:

In one example, various components and/or equipment may be included and/or connected to system 10 to carry out exercises, medical or non-medical.

It will be appreciated by those skilled in the art that other various modifications could be made to the system, process, and method of use without parting from the spirit and scope of this disclosure. All such modifications and changes fall within the scope of the claims and are intended to be covered thereby.

What is claimed:

1. A rehabilitative system, comprising:
a platform frame;
the platform frame extending a length from a first end to a second end thereof;
the platform frame having opposing sides;
the platform frame having a top and a bottom;
the platform frame having a hollow interior;
the platform frame having a storage compartment;
the platform frame having a plurality of access features;
a stable top platform;
the stable top platform extending a length from a first end to a second end thereof;
the stable top platform having opposing sides;
wherein the stable top platform engages the platform frame;
the stable top platform having a top and a bottom;
a first center pillar;
the first center pillar having a first end and a second end;
the first center pillar having opposing sides;
the first center pillar extending a length from a top to a bottom thereof;
the first center pillar having at least one telescoping extension;
the first center pillar having a locking pin;
wherein the locking pin is configured to secure the at least one telescoping extension at various extension lengths;
the first center pillar having a plurality of angle support features;
wherein the plurality of angle support features provide support for the first center pillar;
wherein the plurality of angle support features provide adjustment capabilities for the first center pillar such that the first center pillar can change orientation with respect to the platform frame;
the platform frame having a lip which holds the stable top platform along edges thereof;
wherein the stable top platform is secured by gravity, and a weight of the stable top platform, to the platform frame.
2. A rehabilitative system, comprising:
a platform frame;
the platform frame extending a length from a first end to a second end thereof;
the platform frame having opposing sides;
the platform frame having a top and a bottom;
the platform frame having a hollow interior;
the platform frame having a storage compartment;
the platform frame having a plurality of access features;
a stable top platform;
the stable top platform extending a length from a first end to a second end thereof;
the stable top platform having opposing sides;
wherein the stable top platform engages the platform frame;
the stable top platform having a top and a bottom;

21

a first center pillar;
 the first center pillar having a first end and a second end;
 the first center pillar having opposing sides;
 the first center pillar extending a length from a top to a bottom thereof;
 the first center pillar having at least one telescoping extension;
 the first center pillar having a locking pin;
 wherein the locking pin is configured to secure the at least one telescoping extension at various extension lengths; 10
 the first center pillar having a plurality of angle support features;
 wherein the plurality of angle support features provide support for the first center pillar;
 wherein the plurality of angle support features provide adjustment capabilities for the first center pillar such that the first center pillar can change orientation with respect to the platform frame; 15
 the stable top platform having a plurality of folding features;
 the stable top platform having a plurality of hinge features. 25

3. A muscle release and activation platform, comprising:
 a first platform frame;
 the first platform frame extending a length from a first end to a second end thereof; 30
 the first platform frame having opposing sides;
 wherein the opposing sides of the first platform frame run in approximately parallel spaced relation to one another;
 wherein the first platform frame is generally rectangular in shape; 35
 the first platform frame having a top and a bottom;
 the first platform frame having a hollow interior;
 the first platform frame having a storage compartment;
 the first platform frame having a plurality of access features; 40
 a first stable top platform;
 the first stable top platform extending a length from a first end to a second end thereof; 45
 the first stable top platform having opposing sides;
 wherein the opposing sides of the first stable top platform run in approximately parallel spaced relation to one another;
 wherein the first stable top platform is generally rectangular in shape; 50
 wherein the first stable top platform engages the first platform frame;
 the first stable top platform having a top and a bottom;
 the first stable top platform having a plurality of attachment features; 55
 a first center pillar;
 the first center pillar having a first end and a second end;
 the first center pillar having opposing sides;
 the first center pillar extending a length from a top to a bottom thereof; 60
 the first center pillar having at least one telescoping extension;
 the first center pillar having a plurality of attachment features;
 wherein the plurality of attachment features secure exercise equipment to the first center pillar; 65

22

the first center pillar having a locking pin;
 wherein the locking pin is configured to secure the at least one telescoping extension at various extension lengths; 10
 the first center pillar having a plurality of angle support features;
 wherein the plurality of angle support features provide support for the first center pillar;
 wherein the plurality of angle support features provide adjustment capabilities for the first center pillar such that the first center pillar can change orientation with respect to the platform frame;
 a second center pillar;
 the second center pillar having a first end and a second end; 15
 the second center pillar having opposing sides;
 the second center pillar extending a length from a top to a bottom thereof;
 the second center pillar having at least one telescoping extension;
 the second center pillar having a plurality of attachment features;
 wherein the plurality of attachment features of the second center pillar secure the exercise equipment to the second center pillar; 20
 the second center pillar having a locking pin;
 wherein the locking pin of the second center pillar is configured to secure the at least one telescoping extension of the second center pillar at various extension lengths;
 the second center pillar having a plurality of angle support features; 25
 wherein the plurality of angle support features of the second center pillar provide support for the second center pillar;
 wherein the angle support features provide adjustment capabilities for the second center pillar such that the second center pillar can change orientation with respect to the platform frame;
 a first crossbar; 30
 the first crossbar extending a length from a first end to a second end thereof;
 the first crossbar having an attachment feature at the first end;
 the first crossbar having an attachment feature at the second end;
 the first crossbar having an exterior surface; 35
 the first crossbar having a hollow interior;
 wherein the first crossbar is connected at the first end to the first center pillar;
 wherein the first crossbar is connected at the second end to the second center pillar; 40
 wherein the first crossbar can be put in an engaged position; wherein the engaged position prevents the first crossbar from spinning about a center axis thereof;
 wherein the first crossbar can be put in a disengaged position; wherein the disengaged position allows the first crossbar to spin about the center axis. 45

4. The platform of claim of 3, further comprising:
 a second platform frame;
 the second platform frame extending a length from a first end to a second end thereof; 50
 the second platform frame having opposing sides;
 wherein the opposing sides of the second platform frame run in approximately parallel spaced relation to one another;

23

wherein the second platform frame is generally rectangular in shape;
 the second platform frame having a top and a bottom;
 the second platform frame having a hollow interior;
 the second platform frame having a storage compartment;
 the second platform frame having a plurality of access features;
 a second stable top platform;
 the second stable top platform extending a length from 10 a first end to a second end thereof;
 the second stable top platform having opposing sides;
 wherein the opposing sides of the second stable top platform run in approximately parallel spaced 15 relation to one another;
 wherein the second stable top platform is generally rectangular in shape;
 wherein the second stable top platform engages the second platform frame;
 the second stable top platform having a top and a bottom;
 the second stable top platform having a plurality of attachment features.

24

5. The platform of claim 3, further comprising:
 a second crossbar;
 the second crossbar extending a length from a first end to a second end thereof;
 the second crossbar having an attachment feature at the first end;
 the second crossbar having an attachment feature at the second end;
 the second crossbar having an exterior surface;
 the second crossbar having a hollow interior;
 wherein the second crossbar is connected at the first end to the first center pillar;
 wherein the second crossbar is connected at the second end to the second center pillar;
 wherein the second crossbar can be put in an engaged position; wherein the engaged position prevents the second crossbar from spinning about a center axis thereof;
 wherein the second crossbar can be put in a disengaged position; wherein the disengaged position allows the second crossbar to spin about the center axis of the second crossbar.
